UNITED STATES PATENT OFFICE.

JOHN LAVAGNINO, OF IRVINE, CALIFORNIA.

MORTAR FOR PULVERIZING-MILLS.

No. 876,812.

Specification of Letters Patent.

Patented Jan. 14, 1908.

Application filed January 17, 1907. Serial No. 352,787.

To all whom it may concern:

Be it known that I, JOHN LAVAGNINO, a citizen of the United States, residing at Irvine, in the county of Calaveras and State 5 of California, have invented new and useful Improvements in Mortars for Pulverizing-Mills, of which the following is a specification.

This invention relates to improvements in mortars for pulverizing mills, the objects of 10 the invention being to provide a mortar so constructed that the screens thereof can be easily and quickly changed, and readily cleaned, and so that chips or other foreign material can be readily removed from the 15 interior of the mortar.

My invention also resides in the novel construction, combination and arrangements of parts hereinafter fully specified and particularly pointed out in the claims.

20 In the accompanying drawing, Figure 1 is a front view of the lower portion of a stamp mill mortar constructed in accordance with my invention, one of the screens being in position and the other being removed; Fig. 2 is 25 an enlarged vertical section of line 2—2 of Fig. 1; Fig. 3 is a perspective view of a screen, detached; Fig. 4 is a similar view of a gasket detached; Fig. 5 is a similar view of a screen plate, detached; Fig. 6 is a similar view of a 30 screen frame box, detached.

Referring to the drawing, 1 indicates the mortar of a stamp mill, the lower part only being here shown, said mortar having upwardly extending grooves 2 to receive keys 3, 35 which secure in place a removable wall 4, which extends across the front of the mortar. On the lower portion of said wall 4 are formed upwardly extending channels 6 and 7, the channels at the sides being single, and the 40 channel 6 at the middle being double. In these channels are received screen frames, each of which comprises a rectangular box 8 in which the screen 9 is laid, a plate 10 laid over said screen in said box, and a gasket 11 45 of flexible material interposed between the screen and the box 8. Said box, gasket, and plate are each formed with a rectangular central opening to allow the pulp to splash through the screen.

50 The channels 6 and 7 taper upwards in width, and the plates 10 are likewise tapered

or wedge-shaped, to make a tight fit for the screen frames in said channels. There is preferably provided a handle 12 secured upon the top of each plate 10, for convenience in 55 withdrawing the frame from the channels, although this handle is not absolutely necessary. There is also preferably provided a spring 13 which is attached to the removable wall 14, and the lower side of which is adapted to bear down upon the top of the screen frame, and hold it in position; by pressing the spring to one side, it can be removed from engagement with the screen frame, 60 whereupon the latter can be raised. 65

In order to permit of the ready removal of chips or other foreign substance from the interior of the mortar, there is formed in said wall 4 an opening 14, which is closed by a door 15 sliding in guideways 16. Upon said 70 door and upon the wall 4 are secured posts 17 18, formed at their outer ends with eyes 19, and through said eyes can be passed a pin 20 attached to the frame by a chain. By removing said pin, and sliding the door 15 to 75 one side or the other by means of post 17, the mill man can insert his hand into the interior of the mortar and remove therefrom chips of wood or other foreign substances. Said opening also enables the inner surface of 80 either screen to be quickly wiped off. It is to be understood that the location of this opening is not limited to that here shown, but it may, if desired, be placed directly over either screen opening. 85

I claim:—

In a pulverizing mill having downwardly extending channels on the side of the mortar or pan, individual tapering or wedge-shaped screen frames removably secured in said 90 channels, each frame comprising an apertured box to receive the screen, a gasket of flexible material between said box and screen, and an apertured plate in said box over said screen, substantially as described. 95

In testimony whereof I have hereunto set my hand in the presence of two subscribing witnesses.

JOHN LAVAGNINO.
